UNITED STATES PATENT OFFICE

2,446,788

REFRIGERATED DISPENSING CABINET

Milton Rifkin, Chicago, Ill., assignor, by mesne assignments, to Frez-O-Mat Sales Corporation, a corporation of Illinois

Application August 6, 1945, Serial No. 609,055

11 Claims. (Cl. 62—102)

1

This invention relates to a refrigerated food dispensing cabinet, and has for its principal object the provision of a cabinet in which frozen packages will be held in separated classified compartments, from which the desired package may be removed without opening the cabinet to outside air.

Another object of the invention is to provide a refrigerating system for a cabinet of this character which will always maintain a slight air pressure within the cabinet to prevent warm air from entering from the exterior.

A further object is to provide a dispensing mechanism which will deliver one package at a time; which will be adjustable for various sizes of packages; which will allow fresh packages to be quickly and easily inserted; and which will give a suitable indication when the packages should be replenished.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a front view of the improved refrigerating dispensing cabinet partially broken away to show the interior mechanism;

Fig. 2 is a side view thereof, similarly broken away;

Fig. 3 is an enlarged, detail section through a portion of the cabinet illustrating one of the dispensing mechanisms;

Fig. 4 is a perspective view illustrating one of the package slides employed in the improved cabinet;

Fig. 5 is a detail perspective view illustrating one of the doors of the cabinet in the open position with the insulation removed therefrom;

Fig. 6 is an enlarged detail section across the package slide employed in the improved cabinet, taken on the line 6—6, Fig. 4;

Fig. 7 is a detail view partially in section, illustrating a method of incorporating a heater in the cooling coil of the improved cabinet;

Fig. 8 is a detail perspective view illustrating a package sealing member employed in the improved cabinet;

Fig. 9 is a partial view of the front of the improved cabinet, illustrating an annunciator which

2

may be employed to indicate cabinet conditions;

Fig. 10 is a detail inner face view of a typical door, illustrating an alternate construction therefor;

5 Fig. 11 is a cross section through the alternate form of door, taken on the line 11—11, Fig. 10; and

Fig. 12 is a longitudinal section through the latter door, taken on the line 12—12, Fig. 11.

10 The improved cabinet, designated in its entirety by the numeral 10, may be any of the usual refrigerator constructions, such as having an inner wall 11 and an outer wall 12 separated by suitable heat insulation 13. The cabinet contains 15 storage compartments 14, closed by means of doors 15, and positioned at the bottom thereof. At the top thereof, a motor compartment 16 is provided alongside of a refrigerating compartment 17, the latter being closed by a suitable lid 20 18.

Between the storage compartments 14 and the compartments 16 and 17, the front of the cabinet contains a plurality of small doors 19 closing package delivery openings 20 in the front of the cabinet. A peripheral sealing gasket 21 surrounds each of the doors 19 and contacts the front of the cabinet to seal the door thereto when in the closed position. Each door is also provided with a block of heat insulating material 22 secured 30 thereto by means of an attachment screw 23. The block extends into and closes the opening 20.

A plurality of pairs of slide tracks 24 extend inwardly into the cabinet each pair being in alignment with one of the package openings 20. The 35 slide tracks are secured to the inner wall 11 by means of U-shaped attachment clips 25, and are maintained in proper parallel, spaced relation by means of U-shaped cross braces 26. The tracks 24 are formed from angle-iron with their convex 40 sides turned inwardly to form a support and guide for a row of frozen foods packages, indicated at 27.

Each row of packages is forced forwardly toward the door opening 20 by means of a pusher 45 block 28. The pusher block is arranged to slide along the tracks 24, and is held in slidable relation thereon by means of underlapping clips 29, which extend beneath the tracks 24. The pusher block 28 is urged forwardly by means of a ratchet 50 rack bar 30 having forwardly facing teeth along its upper edge.

The teeth of the rack bar 30 engage a hinged pawl 31 which is mounted on a pivot pin 32 in a pawl bracket 33 on the rear of the pusher block 28. The extremities of the pawl bracket 33 engage

the slides of the rack bar 30 to maintain the block 28 at right angles therewith. The downward movement of the pawl 31 is limited by means of a stop pin 34.

It can be seen that each forward movement of the rack bar 30 will cause the teeth thereof to engage the pawl 31 to move the pusher block 28 forwardly and each rearward movement of the rack bar will cause the teeth thereof to click past the pawl 31 without imparting movement to the pusher block 28. The rack bar is constantly urged inwardly by means of a tension spring 35 which is secured at its forward extremity to a spring hook 36 on the rack bar 30 and at its rearwardly extremity to the rearmost cross brace 26, as shown at 69.

The rack bar 30 is moved forwardly by the opening motion of the door 19 through the medium of a flexible cable 37. The cable 37 extends from a terminal fitting 38 attached to the door 19 beneath a roller 39, attached to the bottom of the frame of he opening 20, thence through a hole in the extremity of the rack bar 30 and back to the fitting 38. The two extremities of the cable are clamped in the fitting by means of a clamp block 40. In the fitting 38 the two reaches of the cable extend beneath a bending pin 41, the position of which is adjustable in a series of pin holes 42.

The doors 19 are mounted on hinge pins 43 extending into hinge bearings 44 on the front of the cabinet. The action of the bending pin 41 is to vary the effective radius from the hinge pins 43 to the point of attachment of the cable 37. That is, if the pin 41 is in the pin hole 42 closest to the axis of the hinge pin 43, the distance the cable is pulled at each opening of the door will be less than it would be if the pin 41 were in the pin hole 42 furthest from the axis of the hinge pin. The pin 41 is pre-set to accommodate packages of various thicknesses. The thicker packages, of course, require a longer movement of the rack bar 30 than the thinner packages.

Since the only means of access to the cabinet is through the doors 19, it is necessary that some means be provided to release the pusher block 28 so that it can be forced inwardly to allow the insertion of fresh packages. This is accomplished in the present invention by mounting the rack bar 30 upon supporting pins 45 in the cross braces 26. The pins 45 pass through guide plates 46 secured on each side of the rack bar 30 and projecting therebelow. The plates 46 are provided with horizontally extending slotted openings 47 through which the pins 45 pass. The inner extremities of the openings 47 are enlarged upwardly as shown at 48. When the door 19 is fully opened, the rack bar 30 will be pulled sufficiently far forward to allow the enlarged extremities 48 of the slots 47 to drop over the pins 45. This allows the entire rack bar to drop so that it will no longer engage the pawl 31. Thus, the pusher block 28 is released and can be forced inwardly by the insertion of fresh packages.

Each time one of the doors 19 is opened, the foremost package 27 of that row of packages will be moved forwardly into the opening 20, and the next succeeding package will be moved into the embrace of a flexible sealing frame which seals the interior of the cabinet from the exterior while the door is open.

The sealing frame consists of four removable elongated strips 88, each of which carries a flexible flap 49 of sheet rubber or similar material, as shown in Fig. 8. The strips 88 are inserted in a peripheral groove 50 around the opening 20.

and are clamped in place therein by means of leaf springs 51, as shown in detail in Fig. 5. The flexible flap 49 of the top and bottom strips 88 is notched as shown at 52 in Fig. 8 to allow the flexible flaps of the side strips 88 to join therewith. The removable strips 88 are for the purpose of accommodating packages of various sizes. These strips will be supplied with flexible flaps 49 of various widths so that the opening in the sealing frame can be adjusted to suit the size of any given package.

It can be readily seen from the above description that a patron can select the desired door 19 containing the desired packages, and by simply pulling this door outwardly and downwardly can cause the pusher block 28 to move the packages in the row sufficiently far forward to deliver one package and seal the cabinet with the next package.

The cabinet is kept filled with cold dehydrated air under slightly higher than atmospheric pressure at all times. This is accomplished by mounting a circulating fan 52 in the refrigerating compartment 17. The fan 52 is driven from a suitable motor 53. A small pressure blower 54 is also driven from the motor 53 and draws its air from the exterior of the cabinet through an air intake tube 55. The fan 52 blows the air through a cooling and dehydrating coil 56 which is kept chilled from any suitable refrigerating mechanism 57.

The cooled, dehydrated air enters the food compartment through an elongated slot 78, adjacent the front wall thereof and flows rearwardly and downwardly to ports 71 in the rear wall and through a port 58 into the storage compartments 14.

The ports 71 open to a return duct 59 at the back of the cabinet which returns the air to the fan 52. It will be noted that the ports 71 increase in size as the bottom of the food cabinet is approached in order to attain a uniform flow through the entire cabinet.

The capacity of the blower 54 is such as to maintain a slight pressure on the air in the housing. When this pressure is reached, no further air will be drawn into the intake 55. Should any air escape through the doors or compartments, the pressure will be lowered and the blower will then build it up to the predetermined point.

The lowermost tubes of the cooling coil 56 are provided with electrical heating elements 60. The current to the heating elements 60 is controlled by means of a clock switch 61, which at pre-set intervals acts to shut off the current to the fan motor 53 and turn the current into the heating elements 60 to heat the coils 56 sufficiently to melt the frost therefrom.

The melting frost drips into a drip pan 62 and is conducted away through a drain pipe 63; thus the coils will be defrosted at regular intervals to maintain the efficiency of the cooling and dehydrating action thereof. During the defrosting period the fan and blower are idle so that warm air is not forced into the food compartment and will be supported by the more dense cold air therein.

The food compartment is provided, of course, with a suitable thermostat 67 for controlling the refrigeration mechanism 57 and the fan motor 53. The thermostat 67 also controls the flow of current to a signal lamp 64 to indicate when the temperature in the cabinet is reaching a dangerous point due to breakdown of the system or current supply.

A series of reload signal lights 65 are also provided, one being positioned over each of the doors 19. These lights indicate to the operator when the merchandise behind that particular door needs replacing. This is accomplished by allowing a tilting arm 66 to rest on the row of packages at the desired point for indication. As long as there is a package beneath the arm 66, the circuit to that signal light 65 will be open. As soon as the last package passes from beneath the arm 66, the latter will tilt a mercury switch 68 downwardly to close the circuit to that particular signal light 65, thus indicating to the operator that that particular compartment needs refilling.

Instead of placing the signal lights over the individual doors, they may be placed in an annunciator box 72, as shown in Fig. 9, wherein the individual compartment signal lights are shown at 65' and the cabinet temperature signal light is shown at 64'.

An alternate construction which may be used in place of the terminal fitting 38 is illustrated in Figs. 10, 11, and 12. This construction employs a slide frame 73 which is mounted on the inside of the door within the insulating block thereon. The slide frame acts as a guide for a nut member 74 which is threaded on a threaded rod 75. The rod 75 is rotatably mounted in any suitable manner, such as by means of an ear 76 on the frame 73.

Rotation of the rod 75 causes the nut member 74 to travel along the frame 73. The rod may be rotated by means of head 77, which is accessible when the door is opened. The cable 37 is attached to a cross pin 78 in the nut member 74. This accomplishes the same purpose as the bending pin 41, that is, it regulates the length of the stroke of the rack bar 30 to accommodate packages of different thicknesses. The stroke can be preset by means of a thickness scale 79 on the inner face of the door, there being a pointer 80 mounted on the nut member 74 for indicating positions on the scale 79.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A dispenser for frozen food packages comprising: a cabinet; a refrigerating medium; a fan forcing air through said refrigerating medium and into said cabinet; means for returning air from said cabinet to said fan; a plurality of doors opening through the front of said cabinet; means for supporting a row of the packages within said cabinet in alignment with each of said doors; means for forcing each row of said packages forwardly when that respective door is opened, and means for supplying air from the exterior to said fan when the pressure in the cabinet falls below a predetermined point.

2. A dispenser for frozen food packages comprising: a cabinet; a refrigerating medium; a fan forcing air through said refrigerating medium and into said cabinet; means for returning air from said cabinet to said fan; a plurality of doors opening through the front of said cabinet; means for supporting a row of the packages within said cabinet in alignment with each of said doors; means for forcing each row of said packages forwardly when that respective door is opened; and motor-operated means for supplying air from the

exterior to said fan when the pressure in the cabinet falls below a predetermined point.

3. A dispenser for frozen food packages comprising: a cabinet; a refrigerating medium; a fan forcing air through said refrigerating medium and into said cabinet; means for returning air from said cabinet to said fan; a plurality of doors opening through the front of said cabinet; means for supporting a row of the packages within said cabinet in alignment with each of said doors; means for forcing each row of said packages forwardly when that respective door is opened; heating means incorporated in said refrigerating means for heating the latter; and a time-operated switch mechanism for closing a circuit to said heating means and opening a circuit to the fan at pre-set intervals.

4. A dispenser for frozen food packages comprising: an insulated cabinet; an insulated cooling chamber in said cabinet; a cooling element in said chamber; a fan for forcing air past said cooling element for cooling and dehydrating the air; a package compartment in said cabinet; a passage communicating between said cooling compartment and said package compartment for the transmission of cooled, dehydrated air thereto; a return duct in said package compartment positioned to return air from the package compartment to said fan; and means for dispensing packages of frozen foods from said package compartment.

5. A dispenser for frozen food packages comprising: an insulated cabinet; an insulated cooling chamber in said cabinet; a cooling element in said chamber; a fan for forcing air past said cooling element for cooling and dehydrating the air; a package compartment in said cabinet; a passage communicating between said cooling compartment and said package compartment for the transmission of cooled, dehydrated air thereto; a return duct in said package compartment positioned to return air from the package compartment to said fan; means for dispensing packages of frozen foods from said package compartment; a motor-operated pressure blower; and an intake conduit to said blower from the exterior of said cabinet for intaking outside air, the discharge from said blower being fed to said fan.

6. A dispenser for frozen food packages comprising: an insulated cabinet; an insulated cooling chamber in said cabinet; a cooling element in said chamber; a fan for forcing air past said cooling element for cooling and dehydrating the air; a package compartment in said cabinet; a passage communicating between said cooling compartment and said package compartment for the transmission of cooled, dehydrated air thereto; a plurality of package openings in the front of said cabinet; a door closing each of said openings; means for supporting a row of packages in alignment with each package opening; and means operable by each door for forcing the row of packages aligned with that door forwardly when the door is opened.

7. A dispenser for frozen food packages comprising: an insulated cabinet; an insulated cooling chamber in said cabinet; a cooling element in said chamber; a fan for forcing air past said cooling element for cooling and dehydrating the air; a package compartment in said cabinet; a passage communicating between said cooling compartment and said package compartment for the transmission of cooled, dehydrated air thereto; a return duct in said package compartment positioned to return air from the package

compartment to said fan; and means for dispensing packages of frozen foods from said package compartment, said first passage being positioned adjacent the front of said cabinet, and said return duct being placed adjacent the rear of said cabinet.

8. A dispenser for frozen food packages comprising: a cabinet; a package compartment in said cabinet; a cooling compartment in said cabinet; a cooling coil in said cooling compartment; a fan positioned adjacent the rear of said cooling compartment and forcing air forwardly through said coil toward the front of said cabinet; a passage at the front of said cabinet communicating between said cooling compartment and said package compartment; and a vertical return duct positioned at the back of said package compartment and communicating at its upper extremity to the intake side of said fan, there being openings in said return duct vertically spaced throughout its length within said package compartment.

9. A dispenser for frozen food packages comprising: a cabinet; a package compartment in said cabinet; a cooling compartment in said cabinet; a cooling coil in said cooling compartment; a fan positioned adjacent the rear of said cooling compartment and forcing air forwardly through said coil toward the front of said cabinet; a passage at the front of said cabinet communicating between said cooling compartment and said package compartment; and a vertical return duct positioned at the back of said package compartment and communicating at its upper extremity to the intake side of said fan, there being openings in said return duct vertically spaced throughout its length within said package compartment, said openings increasing in size as the bottom of said package compartment is approached.

10. A dispenser for frozen food packages comprising: a cabinet; a package compartment in said cabinet; a cooling compartment in said cabinet; a cooling coil in said cooling compartment;

a fan positioned adjacent the rear of said cooling compartment and forcing air forwardly through said coil toward the front of said cabinet; a passage at the front of said cabinet communicating between said cooling compartment and said package compartment; a vertical return duct positioned at the back of said package compartment and communicating at its upper extremity to the intake side of said fan, there

5 being openings in said return duct vertically spaced throughout its length within said package compartment, said openings increasing in size as the bottom of said package compartment is approached; and motor-operated pressure means for drawing exterior air into said cooling compartment rearwardly of said fan.

11. A dispenser for frozen food packages comprising: a cabinet; a refrigerating medium; a fan forcing air through said refrigerating medium and into said cabinet; means for returning air from said cabinet to said fan; a plurality of doors opening through the front of said cabinet; means for supporting a row of the packages within said cabinet in alignment with each of said doors; means for forcing each row of said packages forwardly when that respective door is opened; a peripheral channel about said opening; sealing strips in said channel surrounding said opening; flexible skirts projecting from said 20 sealing strips so as to contact the packages passing through said opening; and means for securing said strips in said peripheral channel.
